Patented May 14, 1918.

UNITED STATES PATENT OFFICE.

HARRY B. WING, OF CRESTED BUTTE, COLORADO.

HANDLE ATTACHMENT.

1,265,852.

Specification of Letters Patent. Patented May 14, 1918.

Application filed August 28, 1917. Serial No. 188,634.

To all whom it may concern:

Be it known that I, HARRY B. WING, a citizen of the United States, residing at Crested Butte, in the county of Gunnison 5 and State of Colorado, have invented new and useful Improvements in Handle Attachments, of which the following is specification.

My present invention has to do with 10 handle fastenings of the wedge type; and it has for its object to provide a wedge fastening that is simple and inexpensive in construction, susceptible of ready application without the employment of skilled 15 labor, and calculated to effectually fasten a hammer head or other tool on its wooden handle in such manner that there is no liability of the head or tool flying off the handle no matter what the usage to which 20 the hammer or other tool is subjected.

With the foregoing in mind, the invention will be fully understood from the following description and claim when the same are read in connection with the drawings, 25 accompanying and forming part of this specification, in which:

Figure 1 is a view illustrative of the mode of applying my novel fastening.

Fig. 2 is a view, partly in section and 30 partly in elevation, showing the fastening as completely applied.

Fig. 3 is a view similar to Fig. 1 but taken at right angles to the latter.

Fig. 4 is an edge elevation of the wedge 35 member *per se* of the fastening.

Similar numerals of reference designate corresponding parts in all the views of the drawings.

By way of example I illustrate my novel 40 fastening in conjunction with a hammer having a head 1 and a wooden handle 2.

The wedge fastening is formed of metal suitable to its purpose, and comprises a wedge member 3 and a locking member 4.

As clearly illustrated the wedge member 45 3 is oblong in cross-section, is tapered toward its inner end, is provided on its long sides, at intermediate points in the length thereof, with lateral teeth 5, and is also provided with a longitudinal-central bore 6. This bore 6 is reduced from an intermediate 50 point of its length to the inner end of the wedge member 3, as indicated by 6^a, so as to form abutments 7 in the bore, for a purpose hereinafter set forth.

The locking member 4 is in the form

of a rod, and has its inner portion bifurcated, as indicated by 8, to form tangs 9 and also has the free ends of the said tangs beveled or sharpened, as indicated by 10. 60

In the practical application and use of my novel fastening, the hammer head 1 is positioned on the handle 2 in the ordinary, well-known manner, after which a slot is formed in the fastened end of the handle, 65

said slot extending in the direction of the length of the hammer head, and being of a size commensurate with that of the wedge member 3. The wedge member 3 is then inserted in said slot and driven home—*i. e.*, 70

until its large end is flush with the fastened end of the handle. With this done, the locking member 4 is driven downwardly in the bore 6 of the wedge member, and into the wood of the handle beyond the inner 75

end of said wedge member. Incidental to this latter step of the operation, it will be manifest that when the inner end of the locking member engages the abutments 7 of the bore 6 in the wedge member 3, which 80

wedge member is also bifurcated as indicated by 11 to form tangs 12, the said tangs 12 will be forced outwardly with the result that the lateral teeth 5 will be embedded their full length in the wood of the 85

handle so as to preclude endwise displacement of the wedge member from the handle, and, at the same time, the handle portion will be considerably expanded in the eye of the hammer head 1 or other tool so that 90

there is absolutely no liability of the hammer head flying off the handle. When the tangs 9 of the rod-like locking member pass out of the inner end of the wedge member, the said tangs will be caused to spread 95

apart by the wood of the handle, and hence will form efficient anchors, well adapted to prevent casual displacement of the locking member from the wedge member and the handle, and at the same time assist in securing the wedge member against accidental 100 movement in the handle, so that the efficiency of the wedge member is not impaired even after a long period of use.

Having described my invention, what I 105 claim and desire to secure by Letters Patent, is:

In a handle fastening, the combination of a tool having an eye, a wooden handle having a portion disposed in said eye, a wedge 110 member, of oblong form in cross-section, embedded in the portion of the handle in

the eye and having lateral teeth on its long sides and also having a longitudinal-central bore extending throughout its length and provided with intermediate abutments and 5 a reduced portion extending inwardly from said abutments; said wedge member being bifurcated from its inner end to a point outwardly beyond the said lateral teeth, and a locking member occupying the said bore 10 of the wedge member and having a bifurcated inner portion and also having the tangs of said bifurcated portion spread apart beyond the inner end of the wedge member, whereby they form anchors in the

handle to lock the whole; the said locking member throughout its length being of a size in cross-section to snugly fit the outer portion of the bore in the wedge member, whereby said locking member serves as it passes through the reduced or contracted portion of the bore to expand the wedge. 15 20

In testimony whereof I have hereunto set my hand in presence of two subscribing witnesses.

HARRY B. WING.

Witnesses:

BENJAMIN SNYDER,

FRED GULLIFORD.
